CLAIM

The ornamental design for a pet bed, as shown and described.

DESCRIPTION

FIG. 1 is a perspective view of a pet bed according to the design.

FIG. 2 is a first side view of the pet bed of FIG. 1, the opposite side view being substantially a mirror image thereof.

FIG. 3 is a front view of the pet bed of FIG. 1.

FIG. 4 is a rear view of the pet bed of FIG. 1.

FIG. 5 is a top view of the pet bed of FIG. 1; and,

FIG. 6 is a bottom view of the pet bed of FIG. 1.

Portions of the pet bed represented in the drawings by broken lines are not considered part of the claimed design.
